HIGHWAY CROSSING SIGNALING SYSTEM

Daniel J. McCarthy, Elgin, Ill., assignor to Associated Electric Laboratories, Inc., Chicago, Ill., a corporation of Delaware

Application May 23, 1934, Serial No. 727,026

6 Claims. (Cl. 246—126)

The present invention relates in general to railway crossing signal control circuits for controlling signals or other apparatus located at intersections of railways and highways to warn those using the highways when a train is approaching.

In the present highway crossing signal systems there is no provision for differentiating between high and low speed trains approaching a crossing, and the crossing signal is operated from a definite and fixed distance from the crossing by all trains regardless of their approaching speed. The operating element, operated by the approaching train for controlling the crossing signal, must be put the maximum distance away from the crossing to give adequate warning against the fastest trains. Under this condition, a train approaching at a slow rate of speed will operate the crossing signal and stop highway traffic longer than is necessary. This long signaling operation before the slowly approaching train actually reaches the crossing has proven dangerous because it invites careless motorists to take chances in passing over the crossing while the train is approaching and the signal is operating.

Accordingly, the main object of the present invention is the provision of new and novel circuit arrangements for differentiating between high and slow speed trains approaching a crossing so that the time length of the warning given by the signal before the train actually reaches the crossing is substantially the same for fast and slow moving trains.

The above and other objects will be apparent from the following specification when read in connection with the accompanying drawing.

Referring now to the drawing, T represents the two rails of a railroad track on which trains approach the highway crossing in the direction indicated by the arrow. Along the inside of one of the rails are placed contactors 2, 3, 4, 5, and 6 which are operated by the wheels of a train when passing thereover. These contactors may be substantially of the same design and operation as disclosed in the application of H. F. Obergfell and G. W. Eickenberg, Serial No. 639,558, filed October 26, 1932, wherein the plunger is operated by the train wheels to cause the operation of the circuit controlling contacts in the associated housing. The corresponding circuit controlling contacts in the present drawing are indicated at 2, 3, 4, 5, and 6 wherein such contacts are operated by the associated plungers represented by

small circles placed along the inside of the lower rail.

The contactor 2 is placed on the left-hand side of the highway crossing, the contactor 3 on the right-hand side of the highway crossing, and the contactors 4, 5, and 6 at varying distances from the crossing best suited to accomplish the desired result as more fully explained hereinafter.

A highway crossing signal, designated as 1, may be of the flashing, audible, or any standard crossing signal type including automatic gates. The contacts of the contactor control circuits of a number of relays, two of which—namely, relays 8 and 9—are of the slow-releasing type, having copper slugs on their armature ends as indicated by the cross-hatched sections thereof. 11, 13, and 26 designate batteries for controlling the operation of the highway signal 1 and the relays. If desired, 26 and 13 may be considered as the same battery. The relays, contactors, and circuits are shown in their normal condition or at a time when there is no signal being given at the highway crossing. Since all of the relays, except relay 10, are normally energized, it is believed advisable to describe the circuits by means of which such relays are maintained in their normal operated positions.

The circuit for maintaining relay 12 energized extends from one pole of battery 13, through armature 17, winding of relay 12, armature of relay 16, and conductors 15 and 14 to the other pole of battery 13. Relay 16 is maintained energized over a circuit extending from one pole of battery 13, armature 17, winding of relay 16, and conductor 14 to the other pole of battery 13. 35 Relay 18 is maintained energized over the following stick circuit: From one pole of battery 13, through the winding of relay 18, armature 23, contacts of contactor 3, conductor 21, lower normally closed contacts of contactor 4, conductor 40 20, contacts of contactor 5, and conductors 19 and 14 to the other pole of battery 13. The circuit for maintaining relay 9 energized extends from one pole of battery 26, through the winding of relay 9, and armature 31 to the other pole of battery 26. Relay 8 is maintained energized over a similar circuit including armature 30. Relay 7 is maintained energized over a locking or so-called stick circuit as follows: From one pole of battery 26, armature 28, winding of relay 7, and 50 contacts controlled by contactor 6 to the other pole of battery 26.

In order to describe the invention it will be assumed that a train is approaching the highway crossing in the direction indicated by the 55

arrow and that in so doing the wheels of the train operate contactor 6 to open the associated contacts. In response to the opening of the contacts controlled by contactor 6 the stick circuit of relay 7 is opened with the result that this relay thereupon deenergizes. At armature 28 relay 7 removes a shunt from around contacts 34 of contactor 4 and at armature 30 opens the circuit to slow releasing relay 8. After an interval slow releasing relay 8 deenergizes and at armature 31 opens the circuit of slow releasing relay 9. If desired, additional slow releasing relays, such as 8 and 9, may be added and connected in a like manner to increase the time interval before the last of such relays deenergize. After an interval the last slow releasing relay, in this case relay 9, deenergizes and at armature 32 completes the circuit for energizing relay 10 over the following circuit: From one pole of battery 26, winding of relay 10, and armature 32 now closed to the other pole of battery. At armature 33 relay 10 closes a shunt around the contacts controlled by contactor 5.

The operation from this point on is different dependent upon the speed of the approaching train or is dependent upon whether the contacts controlled by contactor 5 have been operated by the train before relay 10 has been energized to close contacts 33. In case of a fast train the contactor 5 will be operated before relay 10 has had time to energize and close contacts 33 while in the case of a slow train the relay 10 has had sufficient time to energize and close its contacts 33 to shunt the contacts controlled by contactor 5.

It will now be assumed that the train approaching is a fast train and therefore the contacts controlled by contactor 5 are operated before relay 10 operates its armature contacts 33. Under this condition the operation of the contacts controlled by contactor 5 opens the previously traced stick circuit for relay 18 whereupon relay 18 deenergizes. At armature 23 relay 18 opens a further point in its stick circuit and at armature 17 opens the previously traced circuits of relays 12 and 16 whereupon such relays deenergize. At the contacts controlled by relay 16 a further point is opened in the circuit of relay 12. At armature 25 relay 12 closes the circuit for operating the highway crossing signal 1 over an obvious circuit. From the foregoing it will be seen that a fast train starts the operation of highway signal 1 in response to the operation of contactor 5.

In the case of a slowly approaching train the signal 1 will not start operating until the train reaches and operates the contacts controlled by contactor 4. In response to a slowly approaching train operating contactor 6, relays 7, 8, and 9 deenergize and relay 10 energizes as previously described. In this case relay 10 has energized and closed contacts 33 before the slowly approaching train has operated contactor 5 and therefore, since contacts 33 shunt the contacts controlled by contactor 5, the operation of these contactor contacts is without effect. During the time the contacts controlled by contactor 5 are open the stick circuit for relay 18 is maintained through contacts 33 of relay 10. When the slow train operates contactor 4 the stick circuit of relay 18 is opened at the lower normally closed contacts with the result that relays 18, 16, and 12 deenergize and highway signal 1 is operated as previously described. From the foregoing it will be seen that a fast train operates the highway signal 1 when contactor 5 is operated and a slow

train operates the highway signal when the contactor 4 is operated. Contactors 4 and 5 are therefore placed at sufficient distances from the crossing so that signal 1 will operate for substantially the same length of time before the train, whether fast or slow, actually reaches the crossing.

Each train, regardless of whether it is a fast train or a slow train, prepares the circuits so as to be reset for the next train. Whenever a train operates contactor 4, contacts 34 close an energizing circuit for relay 7 as follows: From one pole of battery 26, conductor 36, contacts 34, conductor 37, winding of relay 7, and contacts controlled by contactor 6 to the other pole of battery 26. At armature 28 relay 7 closes its stick circuit and at armature 30 completes the circuit for energizing slow-to-release relay 8. At armature 31, relay 8, upon energizing, closes the energizing circuit of relay 9. Relay 9, upon energizing, at armature 32 opens the circuit of relay 10 which thereupon deenergizes to open at armature 33 the shunt circuit around the contacts of contactor 5. Relays 7, 8, 9, and 10 are now reset in their normal condition in preparation for the next approaching train.

Contactors 2 and 3 are positioned with respect to each other so that they would be spanned by one or two cars of a train in such a way that when contactor 2 is closed contactor 3 would be immediately opened if the train still spans the crossing. This arrangement prevents the reenergization of relay 18 until the last car has cleared the crossing so that signal 1 will continue to operate as long as any portion of the train is on the crossing. However, when the last car passes the crossing contactor 2 is operated to close its contacts at a time when the contacts controlled by contactor 3 are closed. Under this condition a circuit may be traced for energizing relay 18 as follows: From one pole of battery 18, winding of relay 18, contacts of contactor 2 now closed, contacts of contactor 3 now closed, conductor 21, lower normally closed contacts of contactor 4, conductor 28, normally closed contacts of contactor 5, and conductors 19 and 14 to the other pole of battery 18. At armature 23 relay 18 closes its previously traced stick circuit through contactors 3, 4, and 5 and at armature 17 completes the circuit for energizing slow-to-operate relay 16. Relay 16, upon energizing, completes at its armature a circuit for energizing slow-to-release relay 12 by way of armature 17. Relay 12, upon energizing, at armature 25 opens the circuit to highway signal 1, whereupon the signal ceases to operate. Slow-to-operate relays have copper slugs on their heel end as indicated by the upper full black section of relay 16. All of the apparatus is back to normal condition ready to operate in the same manner as just described for the next approaching train.

In a co-pending application executed by me of even date herewith, Serial No. 727,025, filed May 23, 1934, I have shown and described circuit arrangements whereby the speed of a train between two given points determines whether or not a signal is to be operated. From the foregoing description it will be seen that this feature is also disclosed in the present application wherein the speed of the train between contactors 6 and 5 determines whether signal 1 is to be operated in response to the operation of contactor 5 or in response to the operation of contactor 4. In the co-pending application a railroad grade crossing signal is operated to danger position or remains in

the clear position to govern whether the train may proceed across the railroad grade crossing dependent upon the speed of the train between two given points; while in the instant application the highway crossing signal is operated or not operated in response to the operation of contactor 5 dependent upon the speed of the train between contactors 6 and 5. The co-pending application contains the broader claims directed to the operation of the signals, while the instant application contains the narrower claims directed to the specific disclosures not shown in the co-pending application.

It will be understood that while only one track with traffic in one direction has been illustrated, a similar arrangement is provided for a second track having traffic in the opposite direction. Also while the circuits and arrangements provide for trains having speeds within two limits, it will be understood that any number of limits can be had by multiplying the units in an obvious manner.

What is considered new and is desired to have protected by Letters Patent is set forth in the appended claims.

What is claimed is:

1. In a signaling system for signaling the approach of trains at a crossing, a plurality of contacts located at predetermined points along the track and operable in succession by a train approaching the crossing, a normally energized start relay, a stick circuit for said start relay including the first of said contacts to be encountered by the train, said stick circuit opened in response to the train operating the said first contact to release said start relay, a normally energized signal controlling relay, a stick circuit for said relay including the second and third of said contacts successively operated by an approaching train, slow releasing means initiated in response to the release of said start relay, means operated by said slow-releasing means for shunting the said second contacts after a predetermined time to maintain the stick circuit of said signal controlling relay only in case the said second contacts are operated after said second train operated contacts are shunted, and the operation of said third contacts by the approaching train thereafter opening said stick circuit to release said signal controlling relay.

2. In a signaling system for signaling the approach of trains at a crossing, a plurality of contacts located at predetermined points along the track and operable in succession by a train approaching the crossing, a normally energized start relay, a stick circuit for said start relay including the first of said contacts to be encountered by the train, said stick circuit opened in response to the train operating the said first contact to release said start relay, a normally energized signal controlling relay, a stick circuit for said relay including the second and third of said contacts successively operated by an approaching train, slow-releasing means initiated in response to the release of said start relay, means operated by said slow releasing means for shunting the said second contacts after a predetermined time to maintain the stick circuit of said signal controlling relay only in case the said second contacts are operated after said second train operated contacts are shunted, the operation of said third contacts by the approaching train thereafter opening said stick circuit to release said start relay, and means controlled by some of said contacts when operated for re-

energizing said signal relays and for resetting said slow-releasing means.

3. In a signaling system for signaling the approach of trains at a crossing, a plurality of contacts located at predetermined points along the track and operable in succession by a train approaching the crossing, a normally energized start relay, a stick circuit for said relay including the first of said contacts operated by an approaching train, said stick circuit opened in response to the train operating said first contact to release said relay, slow releasing means initiated in response to the release of said start relay, a normally open shunt circuit around the second of said contacts, means operated by said slow-acting means for closing said shunt circuit around the said second contacts after a predetermined time, a signal controlling relay operated in response to the operation of either said second or third contacts dependent upon whether said shunt circuit is opened or closed at the time the said second contacts are operated by the approaching train, and signaling means at said crossing operated in response to the operation of said signal relay to warn traffic of an approaching train. 25

4. In a signaling system for signaling the approach of trains at a crossing, a plurality of contacts located at predetermined points along the track and operable in succession by a train approaching the crossing, a normally energized start relay, a stick circuit for said start relay, said stick circuit opened in response to an approaching train operating the first encountered one of said contacts to release said start relay, a chain of normally energized slow-releasing relays initiated in their releasing operations in response to the operation of said start relay, a normally open shunt circuit around the second of said contacts, means responsive to the release of the last slow releasing relay in the chain for closing said shunt circuit around the said second contacts, a signal controlling relay, said signal relay operated in response to the operation of either said second or said third contacts dependent upon whether said shunt circuit is open or closed at the time said second contacts are first operated by the approaching train. 35

5. In a signaling system for signaling the approach of trains at a crossing, a plurality of contacts located at predetermined points along the track and operable in succession by a train approaching the crossing, a normally energized start relay, a stick circuit for said start relay, said stick circuit opened in response to an approaching train operating the first encountered one of said contacts to release said start relay, a chain of normally energized slow-releasing relays initiated in their releasing operations in response to the operation of said start relay, a normally open shunt circuit around the second of said contacts, means responsive to the release of the last slow-releasing relay in the chain for closing said shunt circuit around the said second contacts, a signal controlling relay, said signal relay operated in response to the operation of either said second or said third contacts dependent upon whether said shunt circuit is open or closed at the time said second contacts are first operated by the approaching train, and other of said contacts operated by said train for reenergizing said start 60 relay, said other contacts being controlled by the approaching train and other of said contacts operated by said train for reenergizing said start relay, and other of said contacts operated by said train for reenergizing said start relay. 65

6. In a highway crossing signaling system, a highway signal and control means therefor having a normal position, a first, a second, a third, and 70 a fourth position, a stick circuit for said signal and control means, a normally energized start relay, a normally open shunt circuit around the second of said contacts, means responsive to the release of the last slow-releasing relay in the chain for closing said shunt circuit around the said second contacts, a signal controlling relay, said signal relay operated in response to the operation of either 75 said second or said third contacts dependent upon whether said shunt circuit is open or closed at the time said second contacts are first operated by the approaching train, and other of said contacts operated by said train for reenergizing said start relay, and other of said contacts operated by said train for reenergizing said start relay.

a fourth set of contacts located at predetermined points along the railroad track and operable in succession in the order named by a train approaching a highway crossing, a normally closed circuit including said second, said third, and said fourth sets of contacts in series for maintaining said signal control means and signal at normal, a slow operating device initially started in operation in response to the operation of said first set of contacts by a train approaching the crossing, a normally open shunt circuit around said second set of contacts, means operated by said slow operating device when fully operated for closing said shunt circuit around said second set of contacts, 10 said signal control means and said signal always

operated in response to the opening of said series circuit by the train operating said third set of contacts, said signal control means and signal operated in response to the operation of said second set of contacts by the train opening said series circuit only in case said second set of contacts are operated before said slow operating device is fully operated to close said shunt circuit around said second set of contacts, and the operation of said fourth set of contacts by said train maintaining said series circuit open to maintain said signal control means and signal in operated condition. 10

DANIEL J. McCARTHY. 15
